Englewood, Colo.

Filed Aug. 2, 1965, Ser. No. 86,385

Term of patent 14 years

(Cl. D80—3)

FIG. 3.

FIG. 4.

FIG. 1 is a front perspective view of a food display shield embodying my new design;

FIG. 2 is another front perspective view thereof;

FIG. 3 is a top plan view thereof showing the transparent portion in an adjusted position; and

FIG. 4 is an elevational view taken from one end of FIG. 3.

The broken line representation of a second food display shield in FIG. 2 is for purposes of illustration only.

I claim:

The ornamental design for a food display shield, as shown and described.
